UNITED STATES PATENT OFFICE.

WALTER J. FENSTERER, OF ENGLEWOOD, NEW JERSEY.

DESIGN FOR A SHADE.

50,777.

Specification for Design.

Patented May 15, 1917.

Application filed February 28, 1917. Serial No. 151,594. Term of patent 7 years.

To all whom it may concern:

Be it known that I, WALTER J. FENSTERER, a citizen of the United States, and a resident of Englewood, in the county of Bergen and State of New Jersey, have invented a new, original, and ornamental Design for Shades, of which the following is a specification, reference being had to the accompanying drawing, forming part thereof.

The drawing represents a side view of a gas or electric shade showing my new design.

The design consists substantially of a number of parallel annular ribs, and of a

chain showing between two of said ribs. A row of acanthus leaves extends along the innermost rib, and from said row of leaves, extend a series of converging bars that meet a common annular bar at an angle. Beyond this last named bar, appear a number of ovoids that radiate from a common center.

The design is applied to gas shades, electric light shades, light bowls, light domes, light urns and similar articles.

I claim:

The ornamental design for a shade substantially as shown and described.

WALTER J. FENSTERER.
